UNITED STATES PATENT OFFICE.

GIUSEPPE E. TERRANOVA, OF NEW HAVEN, CONNECTICUT.

DENTAL AMALGAM MIXER.

Application filed June 29, 1927. Serial No. 202,257.

This invention relates to improvement in dental amalgam mixers. In mixing amalgam for dental fillings, the ingredients are placed in a capsule, or other container, and shaken by manual or mechanical means to properly combine the ingredients, and this invention relates particularly to mechanical means for shaking a container, the object being to provide a simple device which may be connected to an ordinary dental engine or applied to the spindle of a lathe, and the invention consists in the construction as herein-after described and particularly recited in the claims.

In the accompanying drawings:

Fig. 1 is a front view of a dental amalgam mixer constructed in accordance with my invention;

Fig. 2 is a side view of the same;

Fig. 3 is an enlarged sectional view of the same; and

Fig. 4 is a detached view of the head and spindle.

In carrying out my invention, I employ a ball-like head 5 having an annular cam-groove 6. This head is mounted on a spindle 7 which extends through a frame 8 carrying a base-block 9 upon which the head turns, the lower part of the head and the upper face 25 of the block having raceways 10 and 11 for balls 12. Screwed onto the frame 8 is a housing-cap 13 formed with a slot 14. A rocker 15 sets over the cap and enters the slot 14, and mounted on pins 27 carried by the ends of this rocker are rollers 16 and 17 entering the cam-groove 6. Connected with the rocker are two spring-arms 18 and 19 carrying cups 20 and 21 at their outer ends, between which a capsule or other container 30 35 40 45 50 55 60 65 70 75 80 85 90 95 100 105 110 may be seated. Turned into the lower end of the frame 8 is a handle 23 and through which the spindle 7 also extends, and this handle is chambered to clear the chuck of a dental engine with which the spindle 7 may be connected in the usual way. The ingredients for the amalgam filling mixture are placed in the capsule 22 and this capsule 55 60 65 70 75 80 85 90 95 100 105 110 placed between the cups 20 and 21. The device is held by the handle 23 and the spindle 7 connected with a dental engine which will turn the spindle and thereby rotate the head 5, so as to turn the rocker 15 from side to side, and this produces a corresponding movement of the capsule except that as the capsule is further away from the pivotal point, the extent of movement will be greater, and as

this movement is rapid, the ingredients are soon properly mixed.

In case it is desired to use the device in an ordinary lathe, the handle 23 will be detached from the frame 8 and attached to a hub 24 at one side of the cap 13, which will be provided with a threaded recess to receive the threaded inner end 26 of the handle. Thus, the frame can be supported and held 60 65 70 75 80 85 90 95 100 105 110 against rotation, while the spindle is being revolved, the movement of the arms 18 and 19 being the same as when the device is operated from a dental engine.

This device is extremely simple in construction and effective in operation and readily adapted for use with a dental engine or lathe.

I claim:

1. A dental amalgam mixer, comprising 75 a frame, a head mounted on a spindle extending through said frame, said head formed with an annular cam-groove, a slotted cap connected with said frame and enclosing said head, a rocker entering the slot in the cap 80 and provided at its ends with rollers traveling in the cam-groove in the head, spring arms connected with said rocker, and means for mounting a capsule between the ends of said arms.

2. A dental amalgam mixer, comprising a head having an annular cam-groove, a frame to support said head, said head provided with a spindle extending through said frame, a handle detachably connected with said frame, a slotted cap attached to said frame and enclosing said head, a rocker entering the slot in the cap and provided at its ends with rollers traveling in said groove, and two spring arms connected with said rocker, 95 said arms provided at their outer ends with seats for a container for amalgam.

3. A dental amalgam mixer, comprising a head having a cam-groove, a frame supporting said head, a spindle connected with said head and extending through said frame, a chambered handle detachably connected with the inner end of said frame, a slotted cap attached to said frame and enclosing said head, a rocker entering the slot in the cap and carrying rollers at its ends traveling in said groove, spring-arms connected with said rocker, and seats at the outer ends of the arms for a container for amalgam, said frame formed on one side with a threaded opening 110 for the connection thereto of the said handle.

4. A dental amalgam mixer, comprising a

frame, a bearing-block in said frame, a head mounted on a spindle extending through said frame, balls between said head and block, said head formed with an annular cam-groove, a slotted cap connected with said frame and enclosing said head, a rocker entering the slot in the cap and provided at its

ends with rollers traveling in the cam-groove in the head, spring arms connected with said rocker, and means for mounting a capsule between the ends of said arms.

In testimony whereof, I have signed this specification.

GIUSEPPE E. TERRANOVA.
